UNITED STATES PATENT OFFICE.

JOSEPH TOMLINSON, OF CHICAGO, ILLINOIS.

PRINTING-PLATE.

1,151,500.

Specification of Letters Patent. Patented Aug. 24, 1915.

Application filed November 3, 1913. Serial No. 798,826.

To all whom it may concern:

Be it known that I, JOSEPH TOMLINSON, a citizen of the United States, residing at Chicago, in the county of Cook and State 5 of Illinois, have invented certain new and useful Improvements in Printing-Plates, of which the following is a specification.

My invention relates to improvements in printing devices and has more particular 10 reference to printing plates of the character used generally in addressing machines and the like.

One of the objects of my invention is to provide an improved printing plate which 15 will be simple, durable and reliable, and efficient and extremely inexpensive to manufacture.

Other objects of my invention will appear hereinafter.

20 In the drawings: Figure 1 is a perspective view of a stack of printing plates embodying my invention; Fig. 2 is a perspective view of a single plate; and Fig. 3 is a sectional view of two of my printing plates 25 arranged to illustrate the manner in which the plates stack readily.

In the drawings I have illustrated a printing plate which is intended to be used in printing and addressing machines. Plates 30 of this character are usually provided each with a single address. They are placed in a stack or pile in the magazine or galley of an addressing machine, and, from this magazine, the machine takes the plates one by 35 one in successive order, prints the addresses on the paper or other material fed to the machine, and then discharges the plates in the same order in a stack. The stacks of plates are generally kept properly indexed 40 and arranged in the drawers of an index cabinet. It is essential, therefore, that these plates must be of such character that they can be made at an extremely small cost. A very important requirement is that they 45 must be exact duplicates of each other from the standpoint of structure, that is to say, their structure must be such that they can be manufactured in large quantities in exactly the same size and dimensions, so that 50 they will properly pass through the machines freely and without sticking or clogging the machine. Not only must the plates have these characteristics, but it is extremely essential that they be capable of readily and 55 freely stacking, both in the cabinet drawers and in the machine in which they are used.

This is apparent for the reason that they are handled in such large quantities that the operator's hands seldom touch them. In consequence, they must necessarily be of 60 such character that they will stack readily and almost automatically, so to speak. The plate which I have shown in the drawings meets all of these requirements. It is preferably composed of a single piece or plate A 65 of sheet metal of the proper length, width and thickness, and each plate must be of the same dimensions as each other plate. Each plate, as before mentioned, carries preferably a single name and address, this being 70 in the form of embossed type 1, struck up integrally from the body of the plate on one side thereof. Since the type project from one side of the plate, it is necessary to provide some means for protecting the type 75 when a large number of these plates are arranged in a stack, and for this reason I prefer to turn or roll over the longitudinal edges B of the sheet metal in such manner that they form protecting ribs. The thickness of the plate at these edges is slightly 80 greater than the height of the type above the surface of the plate, so that the ribs prevent the plates from rubbing or contacting with the type. I prefer to turn the 85 edges B over onto the side of the plate opposite to that from which the type project, the purpose being to leave the type side of the plate otherwise flat and clear, so that it will not interfere with the printing operations. By arranging these turned over ribs 90 or edges on the side or face of the plate opposite to the type side or face thereof, the ribs of one plate contact with the type side or face of the next adjacent plate in the stack 95 and, since the ribs are of slightly greater thickness than the height of the type, they prevent the type on said next adjacent plate from coming in contact with the rib face of the plate. In the plate structure shown, the 100 ribs are made integral with the plate itself and are simply made by turning over or rolling the edge portions of the plate. The extreme edges C are brought down into intimate contact with the surface of the plate 105 so that in effect these edges might almost be said to merge with the surface of the plate. The edge portions are preferably inclined slightly toward each other, so that the faces D, so to speak, of the ribs, form somewhat 110 of an incline.

This construction is very essential, since

it is obvious that should any one or more of the plates in a stack shift relatively to the others, or become disarranged or out of alignment, the ribs of one plate will not interfere in any way with the stacking or realining of the plates. In other words, the rounded edge portions of the displaced plate will ride up on the ribs of the next adjacent plate upon whose ribs said displaced plate rests. In fact, the disarranged or displaced plates will readily move into place by simply agitating or shaking the stack in the drawer. This is illustrated more particularly in Fig. 3, which shows two plates, one resting upon the other. The plates, as will be seen, are relatively displaced, the rib edges of one plate being in such position that when a slight pressure is applied to the edge of it it will ride up on the ribs of the plate upon which it is resting. These ribs or flanges also have another very important function to perform, and that is the stiffening of the plates so that they will withstand the pressure incident to the printing operations, which pressure oftentimes is considerable and would, if the plates were not strengthened, operate to distort the plates.

It will thus be seen that my invention meets all of the requirements by a structure which is not only simple but can be made at an extremely low cost and can be manufactured to exact dimensions.

What I claim is:

1. A printing plate of the class described comprising a flat piece of metal having type

projecting from one face thereof and having its edges thickened on the other face of the plate to a degree slightly greater than the height of the type, said thickened edges having faces inclined toward and substantially merging with the last mentioned face of the plate. 40

2. A printing plate of the class described comprising a flat rectangular plate of sheet metal having integral type struck from one face thereof and having two parallel edge portions turned over onto the opposite faces of the plate, said turned edges forming protecting ribs of a greater thickness than the height of the type and being formed inclined toward the last mentioned face and each other. 50

3. A printing plate of the class described comprising a flat rectangular plate of sheet metal having type struck up on one side 55 thereof, its longitudinal edge portions from end to end being rebent and disposed on the reverse side from said type, and the rebent portions disposed inclined to said last mentioned side with the extreme edges resting 60 against the latter, and the edges at the ends of the plate being disposed flat.

In testimony whereof I have signed my name to this specification, in the presence of two subscribing witnesses, on this 31st day 65 of October, A. D. 1913.

JOSEPH TOMLINSON.
